UNITED STATES PATENT OFFICE.

JEAN BÈCHÉ, OF HÜCKESWAGEN, GERMANY.

APPARATUS FOR MAKING FILES.

1,000,888.

Specification of Letters Patent. Patented Aug. 15, 1911.

Application filed August 9, 1910. Serial No. 576,318.

To all whom it may concern:

Be it known that I, JEAN BÈCHÉ, a subject of the King of Prussia, German Emperor, residing at Hückeswagen, in the Province of the Rhine, Kingdom of Prussia, German Empire, have invented certain new and useful Apparatus for Making Files, of which the following is a specification.

This invention relates to an apparatus for making files.

The novelty resides in the particular construction set forth and then particularly pointed out in the claim.

The apparatus for making cycloidal shaped file teeth will now be described more exactly by aid of the drawing.

The cutter *f* is formed of a steel ring or tube in which in a radial direction, a spiral is cut with a pitch equal to the teeth divisions of the file (see Figures 2, 7 and 6). This threading is provided with cuts and reversed. Hereby are produced the cutting teeth (see Figs. 4 and 7). In order that every separate tooth of the cutter must do its determined work, the teeth are also arranged in the axial direction as a spiral, and this moreover with a pitch equal to the depth of the teeth.

Fig. 8 shows the cross section of the cutter and *c* indicates the pitch of the cutter teeth in the axial direction, consequently the tooth division of the file, while *b* indicates the pitch of the cutting teeth in the axial direction.

Fig. 6 shows an elevation of the cutter and the axial pitch is shown like *b* on an enlarged scale for increased clearness. The distance *c*—*c'*—*b* is consequently the depth of the file teeth.

Fig. 4 shows the developed tooth line of the cutter teeth. The tooth *c* lies on the left side level upon the file (Fig. 3). Each following cutter tooth lies by the amount *b* of the tooth depth divided by the number of the cutter teeth deeper than the horizontal. Consequently if the last tooth *c'* has passed the file, then one file tooth is cut finished. Fig. 3 shows therefore the beginning of the cutting, Fig. 5 the completion of a file tooth.

Moreover Fig. 2 shows how the cutter rotates over the file *i*. The lowest point of the cutter teeth *c'* has passed the file and the tooth is finished, while the highest teeth *c* and the next following teeth of the cutter have already begun a new tooth. In the arrangement of the cutter spirals shown

(see Figs. 2, 6, 7) there consequently corresponds to each turn of the cutter the completion of one file tooth.

In the construction of files with small tooth divisions, it would be irrational to make use of an entire cutter revolution for the making of a single file tooth. For such work I arrange the cutter with several threadings. Fig. 9 shows the arrangement of four threadings. Here also a corresponds to the tooth division, and in this arrangement at one-fourth of a turn of the cutter a tooth is produced.

The file shown has a great practical advantage. The teeth of the file are, in contrast to known files, curved toward the fang, so that viewed from the fang-end, they appear to be convex, thus the file grip is better in working. Whereas the known file-teeth, curved in an opposite direction, push the material slantingly outward, force components, which try to push the material toward the middle of the file are created in the new file. This difference causes often in the known files, a sliding on the material, but in the new file, a better gripping is produced. Especially can this be seen if an edge or corner has to be filed in which the file only files lengthwise. If the file-teeth are curved concave to the fang, the counter-pressure, caused by the material, pushed slantingly outward, acts through a component on the file in such a manner that the same glides off the edge. But, if the teeth are convex to the fang, the counter-pressure of the material causes the file to grip firmly. Of course, this advantage is not only for cycloidal formed teeth, but also for other teeth curved toward the fang. Practically the best form of the teeth is the cycloidal form.

Fig. 1 shows the entire section of the cutter and its arrangement upon the file. The cutter is somewhat inclined to the surface of the file, so that the teeth opposed to the cutting teeth do not injure the already cut file. The file itself is fixed upon a support which, by well known means, draws the file in the horizontal direction under the cutter. The speed of the file is of course so regulated that according to Figs. 2 and 7 at each revolution of the cutter the file moves on by the amount of one tooth division, while according to the arrangement shown in Fig. 9 the file must move on by the four-fold amount of the tooth division.

In order that under all circumstances a definite depth of teeth is assured, there is provided above the cutter holder g an adjustable projection as shown in Fig. 1 in the shape of a guide ring e which is adjustable by means of a screw. This ring made of hard steel, supports itself upon the file to be cut, and is so arranged that the deepest cutter tooth will not cut deeper than necessary. 5

10 By the nut d , the guide ring is adjusted, the cutter is put into rotation, and the cutting of a file then takes place automatically.

With regard to the circumstance that the points of the file teeth in the middle are cut deeper than those at the edges, the following should be noted. In Fig. 10 the spiral line of the cutter tooth points is indicated in dotted lines, namely, a circular line described around the center of the cutter is 15 shown in dotted lines, from the curves visible upon the file, of which the outer one is shown full and the inner one dotted, which at the beginning of the cutting is effected 20 by, the cut produced by the first tooth c while the fully drawn inner line is produced 25 by the last teeth c^1 . As, however, the inner circle has smaller radii than the outer one, the parts x will be cut away from the already previously cut tooth curves, as is indicated 30 in section in Fig. 11. From this it will be obvious that the tooth backs upon both sides of the file are more cut away than in the middle of the file where the same have their full height. By this means I 35 attain that the points of the file teeth are produced in a straight line (Fig. 13) which is not possible with a circular cutter of the already known kind, because by reason of the inclined position of the cutter more is 40 cut away in the center than at the sides of the file, and a hollow toothing is produced as shown in Figs. 10 and 14. A file cut in

this manner cannot be used because the outer edges take deeper hold than the inside. The line shown dotted in Fig. 13 indicates the heights which are cut away by the cutter according to the present invention. 45 Finally it should be mentioned that the process, as may be seen, has other considerable practical advantages. There is not only, as has already been said, a continuous 50 working, which is always preferable to an intermittent one, but there is always a definite depth of tooth and pitch of tooth. Moreover curved files can be made under the 55 aforesaid conditions. Further, the work of cutting can be effected without making any great requirement on the intelligence of the workmen and progresses automatically in the easiest manner. 60

Any suitable means adapted to the purpose may be employed for feeding the file blank while the same is being operated upon, such means, however, are not herein shown. 65

Having now particularly described and ascertained the nature of my said invention and in what manner the same is to be performed, I declare that what I claim is:

In an apparatus for making files, a 70 toothed cutter of tubular form, having a series of teeth at the end thereof arranged circumferentially and spirally with a pitch equal to the spaces between the teeth of the file to be produced, said cutting teeth being 75 of gradual increasing depth or length, substantially as shown and described.

In testimony, whereof I have signed my name to this specification in the presence of two subscribing witnesses.

JEAN BÉCHÉ.
